UNITED STATES PATENT OFFICE

AMON ALTON HUTTO, OF SAMSON, ALABAMA

PLOW ATTACHMENT

Application filed September 1, 1928. Serial No. 303,559.

This invention relates to an attachment especially designed for use in connection with steel beam plows, the primary object of the invention being to provide a subsoiling attachment at the rear of the usual plow.

Another object of the invention is to provide an attachment which may be employed in connection with shovel sweep or turning plows eliminating the necessity of making alterations in the usual plow construction to secure the attachment in position.

A still further object of the invention is to provide a device of this character which may be adjusted to regulate the depth of operation of the subsoiler.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view illustrating a plow equipped with a subsoiler constructed in accordance with the invention.

Figure 2 is a sectional view taken on line 2-2 of Figure 1.

Figure 3 is a plan view of the plow and subsoiler.

Figure 4 is a sectional view taken on line 4-4 of Figure 1.

Figure 5 is a sectional view taken on line 5-5 of Figure 1.

Referring to the drawings in detail, the reference character 5 designates a plow beam, to which the attachment forming the essence of the present invention, is secured.

The subsoiling attachment embodies curved beams 6 and 7 respectively which

have their forward ends formed with openings 8 to accommodate the bolt 9 for securing the attachment and the brace bars 10, forming a part of the attachment, to the plow proper.

The beams 6 and 7 are held in spaced relation with each other by means of the bar 11 which is formed with a plurality of spaced openings 12 to accommodate the bolt 13 which also passes through the arms 14 that extend rearwardly and to which the handles 15 of the plow are adjustably connected.

At the lower end of the bar 11 is an opening to receive the bolt 16 that extends through the ear 17 extending from the rear of the plow, to which the device is secured, and it will be seen that by loosening these bolts adjustments may be made to regulate the depth of operation of the plow or the subsoiler forming the subject matter of this invention.

The rear ends of the beams 6 and 7 curve downwardly where they support the subsoiling blade 18 which is secured in position by means of the bolt 19 that extends between the beams 6 and 7. This bolt 19 also extends through an opening in the subsoiling member 20 which embodies laterally extended blades 21 sharpened along their lower edges defining cutting edges 22.

From the foregoing it will be obvious that due to the construction shown and described, a subsoiler may be secured to the usual plow to accomplish the subsoiling result, and it will also be seen that the device may be used for siding corn, cotton, peanuts or the like or with a turning plow or shovel sweep to better condition the soil.

I claim:

A subsoiling attachment for plows, including spaced beams having curved lower ends, means for securing the front ends of the spaced beams to the beam of a plow, a curved subsoiling blade fitted against the

curved ends of the spaced beams, a bolt extending between the spaced beams and through the subsoiling blade, a subsoiling member embodying laterally and rearwardly extended blades and a central offset portion,
5 said bolt extending through the offset portion to connect the curved subsoiling blade and subsoiling member, and a nut on the bolt positioned in the offset portion to secure the subsoiling blade and subsoiling member
10 in position.

In testimony that I claim the foregoing as my own, I have hereto affixed my signature.

AMON ALTON HUTTO.
